UNITED STATES PATENT OFFICE.

HERMAN JACOBSON, OF NEW YORK, N. Y.

DESIGN FOR A TEXTILE FABRIC.

No. 39,067.

Specification for Design.

Patented Feb. 4, 1908.

Application filed December 12, 1907. Serial No. 406,246. Term of patent 3½ years.

To all whom it may concern:

Be it known that I, HERMAN JACOBSON, a citizen of the United States, residing in the borough of Brooklyn, county of Kings, city and State of New York, have invented a new, original, and ornamental Design for Textile Fabric, of which the following is a specification, reference being had to the accompanying drawing, forming part thereof.

The figure is a plan view of a portion of the textile fabric, showing my design.

I claim:

The ornamental design for textile fabric, as shown.

HERMAN JACOBSON.
